UNITED STATES PATENT OFFICE.

HAL R. MARTIN, OF EDGERTON, WISCONSIN.

DESIGN FOR A TRAFFIC-POST.

52,916.

Specification for Design.

Patented Jan. 28, 1919.

Application filed July 30, 1918. Serial No. 247,451. Term of patent 14 years.

To all whom it may concern:

Be it known that I, HAL R. MARTIN, a citizen of the United States, residing at the city of Edgerton, county of Rock, State of Wisconsin, have invented a new, original, and ornamental Design in a Traffic-Post, of which the following is a specification.

In the drawing the figure is a perspective view of my improved traffic post.

I claim:

The ornamental design for a traffic post, as shown.

HAL R. MARTIN.
